UNITED STATES PATENT OFFICE

100,839

DESIGN FOR A PULL FOR SLIDE FASTENERS

Colin D. Barrett, Watertown, Conn., assignor to
Hookless Fastener Company, Meadville, Pa., a
corporation of Pennsylvania

Application January 24, 1936, Serial No. 60,796

Term of patent 14 years

To all whom it may concern:

Be it known that I, Colin D. Barrett, a citizen
of the United States, residing at Watertown, in
the county of Litchfield and State of Connecticut,
have invented a new, original, and ornamental
Design for a Pull for Slide Fasteners, of which
the following is a specification, reference being
had to the accompanying drawing, forming a
part thereof.

In the drawing:

Fig. 1 is a plan view of a pull for slide fasteners
showing my new design; and

Fig. 2 is a side view of the same.

I claim:

The ornamental design for a pull for slide fas-
teners, as shown.

In testimony whereof I affix my signature.

COLIN D. BARRETT.
